UNITED STATES PATENT OFFICE.

AUGUST G. LIEBMAN, OF CHICAGO, ILLINOIS.

RAIL-CHAIR.

1,279,729.

Specification of Letters Patent. Patented Sept. 24, 1918.

Application filed February 15, 1917, Serial No. 148,866. Renewed June 13, 1918. Serial No. 239,880.

To all whom it may concern:

Be it known that I, AUGUST G. LIEBMAN, a citizen of the United States, residing at Chicago, in the county of Cook and State of Illinois, have invented certain new and useful Improvements in Rail-Chairs, of which the following is a specification.

This invention relates to railway track appliances and more particularly to rail chairs.

10 The object of the invention is to provide a rail chair particularly adapted for use on soft wood ties or treated soft wood ties and which will permit of both vertical and lateral adjustment of the rails for surface and 15 gage without disturbing the primary fastening devices.

A further object is to provide a rail chair, the construction of which is such as to render unnecessary the use of bolts extending 20 through the tie and, consequently, obviate the corrosion of bolt heads on the underside of the tie which often occurs in saline soils.

A further object is to provide the bed plate with an overhanging abutment adapted 25 to receive a cap screw, the free end of which seats in a socket in the rail clamping member and serves to hold said member in engagement with the base flange of a rail.

A further object is to provide the bed plate 30 of the chair with depending half dowels which act as binders and also serve to prevent checks and cracks in the tie from expanding or widening as the tie seasons and, therefore, prevent splitting of the tie.

35 A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

45 In the drawings:

Figure 1 is a perspective view of a rail chair embodying the present invention;

Fig. 2 is a top plan view;

Fig. 3 is a transverse sectional view;

50 Fig. 4 is a bottom plan view with the tie removed.

Corresponding and like parts are referred to in the following description and indicated in all the views of the drawings by the

55 same reference characters.

Referring to the drawings, A represents a rail having a standard cross section, and B a tie supporting the rail. Mounted upon the cross tie B is a bed plate 5, preferably a malleable casting, although the plate may be otherwise formed, if desired. The bed plate 5 is substantially rectangular in shape and preferably extends the entire width of the upper surface of the tie, as shown.

Depending from the bed plate 5 and preferably formed integral therewith, are depending half dowels or extensions 6, one of said extensions being preferably arranged near each corner of the plate and all of said dowels having their open sides facing in the same direction. The bed plate 5 is permanently secured to the upper surface of the cross tie by means of primary fastening devices, preferably in the form of screw spikes

7 arranged at diagonal corners of the bed plate and which pass through suitable openings 8 formed in said bed plate, as shown. The half dowels 6 not only assist in anchoring the bed plate on the cross tie but also act as binders and serve to prevent the checks and cracks in the tie from widening or expanding as the tie seasons and, therefore, prevent premature splitting of the tie. Spaced inwardly from the opposite ends of the bed plate 5 are upstanding abutments 9, preferably formed integral with the plate and extending approximately one-half the width thereof, these abutments being arranged at diagonally opposite corners of the bed plate and being connected therewith by

80 terminal webs 10 and 11. The abutments 9 are further reinforced and strengthened by a plurality of buttressing webs 12 which extend from the upper ends of the abutments 9 to the adjacent end of the plate, as shown. Each abutment 9 is provided with an inwardly extending arm 13 which overhangs the bed plate 5 and is provided with a threaded opening 14 adapted to receive a cap screw

15. The opening in the arm 13 is surrounded by a reinforcing collar 16, the upper surface of which is preferably flat, said reinforcing collar being connected with the upper end of the adjacent abutment 9 by a reinforcing rib 17, which forms in effect a 105 continuation of the central buttressing web 12.

Arranged beneath each arm 13 is a rail clamping member 18, preferably octagonal in shape and provided with a depending ec- 110

centric portion 19 adapted to bear against the adjacent longitudinal edge of the base flange of the rail. Each rail clamping member is also provided with a circumferential flange 20 having its lower face inclined and its marginal edge formed with a plurality of angular faces 21 adapted to bear against the inner faces of the adjacent abutments 9 whereby to hold the rail in different positions of lateral adjustment with respect to the bed plate. Each clamping member is also formed with a centrally disposed socket 22 adapted to receive the tapered end of the adjacent cap screw 15 so that when said cap screw is tightened the clamping member will be securely held in engagement with the base flange of the rail and thus hold said rail from accidental displacement.

The inner webs 11 are preferably longer than the outer webs 10 and are of sufficient height and length to form in effect side abutments for engagement with the rail clamping members 19, as best shown in Fig. 2 of the drawings. By loosening the cap screws 15 and rotating the clamping members 19, the rail may be adjusted laterally on the bed plate for gage, while by adjusting the cap screws vertically and inserting a shim 23 beneath the rail, said rail may be adjusted vertically for surface, it of course being understood that after adjustment of the rail has been effected the cap screws will be tightened so as to firmly hold the rail clamping members 19 in proper position. Owing to the fact that the depending dowels 6 form auxiliary anchoring devices for the bed plate, the use of bolts extending entirely through the tie is rendered unnecessary and, consequently, corrosion of bolt heads on the underside of the tie, which often occurs in saline soils, is obviated. It will further be noted that certain of the half dowels 6 are so arranged as to accommodate the threaded ends of the adjacent screw spikes 7 thereby serving to reinforce and strengthen the spikes and receive the lateral thrust thereon. This form of chair and fastening device is extremely simple in construction and can be manufactured at a minimum cost.

Having thus described the invention, what is claimed as new is:

1. A rail chair including a bed plate having fixed upstanding abutments provided with overhanging portions, primary fastening devices for the bed plate, rail clamping members for holding a rail in different positions of lateral adjustment with respect to the bed plate, and fastening devices extending through the overhanging portions of the abutments and engaging the rail clamping members.

2. A rail chair including a bed plate having upstanding abutments provided with overhanging portions and side portions, rail

clamping members engaging the upstanding abutments and side portions thereof for holding a rail in different positions of lateral adjustment with respect to the bed plate, and fastening devices extending through the overhanging portions of the abutments and engaging the rail clamping members. 70

3. A rail chair including a bed plate having upstanding abutments provided with overhanging portions, rail clamping members for holding a rail in different positions of lateral adjustment with respect to the bed plate and having sockets formed therein, and fastening devices extending through the overhanging portions of the abutments and fitting in said sockets. 75

4. A rail chair including a bed plate having a fixed upstanding abutment provided with a portion overhanging the bed plate, a rail clamping member movable to different positions of adjustment with respect to the bed plate, and a fastening device extending through the overhanging portion of the abutment and engaging the rail clamping member. 80 85

5. A rail chair including a bed plate having upstanding abutments provided with overhanging portions formed with threaded openings, rail clamping members having sockets therein, and screws threaded in the openings in the overhanging portions of the abutments and engaging the sockets in the rail clamping members. 90 95

6. A rail chair including a bed plate having depending half dowels for engagement with a cross tie and provided with upstanding abutments having overhanging portions, rail clamping members movable to different positions of adjustment with respect to the bed plate, and fastening devices extending through the overhanging portions of the abutments and bearing against the rail clamping members for holding said rail clamping members in different positions of adjustment. 100 105 110

7. A rail chair including a bed plate having depending half dowels adapted to be embedded in a cross tie and provided with upstanding abutments having overhanging portions, primary fastening devices extending through the bed plate and within the adjacent half dowels, rail clamping members having sockets formed therein, and screws threaded in the overhanging portions of the abutments and engaging the sockets in the rail clamping members. 115

8. A rail chair including a bed plate having depending half dowels arranged one near each corner of the bed plate and adapted to be embedded in a cross tie, all of said dowels opening in the same direction, abutments projecting upwardly from the upper surface of the bed plate and provided with overhanging portions, rail clamping members arranged near the abutments, and fas- 120 125 130

tening devices extending through the overhanging portions of the abutments and engaging the rail clamping members.

9. A rail chair including a bed plate having depending half dowels adapted to be embedded in a cross tie and provided with upstanding abutments arranged at diagonal corners of the bed plate and provided with overhanging portions, primary fastening devices for the bed plate, rail clamping members having tapered sockets formed therein, and fastening devices threaded in the overhanging portions of the abutments and provided with terminal tapered portions adapted to engage the walls of the sockets in the rail clamping members.

10. A rail chair including a bed plate having upstanding abutments provided with overhanging portions formed with threaded openings and having reinforcing collars surrounding said openings, buttressing webs connecting the abutments with the bed plate, one of said buttressing webs being extended to and connected with the adjacent reinforcing collar, rail clamping members having sockets formed therein, and screws threaded in the openings in the overhanging portions of the abutments and engaging the rail clamping members.

11. The combination with a cross tie, of a bed plate having depending dowels embedded within the tie and having upstand-

ing abutments provided with overhanging portions, a rail adapted to rest on the bed plate or a shim, rail clamping members arranged beneath the overhanging portions of the abutments, and fastening devices extending through the overhanging portions of the abutments and engaging the rail clamping members for holding the rail in different positions of lateral and vertical adjustment with respect to the bed plate.

12. The combination with a cross tie, of a bed plate having depending half dowels embedded in the tie and having their side faces all opening in the same direction, said bed plate being provided with upstanding abutments having overhanging portions and provided with side abutments integral with the bed plate, primary fastening devices extending through the bed plate and fitting adjacent half dowels, a rail adapted to rest on the bed plate or a shim, rail clamping members for holding the rail in different positions of lateral and vertical adjustment with respect to the bed plate and having portions thereof adapted to bear against the upright and side abutments, and fastening devices extending through the overhanging portions of the abutments and engaging the rail clamping members.

In testimony whereof I affix my signature.

AUGUST G. LIEBMANN. [L.S.]
